Attorney

UNITED STATES PATENT OFFICE

JOHN ACHATZ, OF HOOPER, COLORADO, ASSIGNOR OF ONE-HALF TO RUDOLPH B. SPRUILL, OF HOOPER, COLORADO

CLEVIS

Application filed August 15, 1928, Serial No. 299,745. Renewed February 26, 1930.

The present invention pertains to new and useful improvements in clevis structures of the type employing a detachable pin. The invention relates more particularly to securing means whereby the pin member will be retained on the clevis against accidental disengagement, yet possessing means whereby the pin may be easily disengaged from the clevis when desired.

10 The prime object of the invention resides in the provision of a pin member for clevises having means whereby the pin will be prevented from rotation, and wherein additional means is provided for retaining the pin in 15 position against accidental displacement.

An additional object of importance resides in the provision whereby the pin is retained in position, yet being capable of quick adjustment to permit the removal of the pin.

20 After considering the following specification and claim other important objects and advantages of the invention will become apparent.

In the drawing:

25 Figure 1 is a side elevation of the improved clevis.

Figure 2 is a side elevation of the clevis in partial sectional view, and

Figure 3 is an edge elevation of the device.

30 Referring to the drawings wherein like numerals designate like parts, a U-shaped body 1 such as is usually employed in clevis structures is formed with an opening adjacent each end thereof. An opening 2 is formed 35 through one leg of the body 1 slightly inwardly from the opening and the end thereof.

A pin 3 is adapted to be arranged through the openings at the ends of the body 1 and is provided with a laterally disposed head 4 at 40 one end thereof. The head 4 is formed with a recess 5 extending inwardly from its free end while a depending tip 6 is provided at the under side of the head 4 and for engagement within the opening 2.

45 A spring leaf 7 provided with one end portion reduced, while its opposite end is pivotally secured to the U-shaped body 1 by a rivet 8. The reduced end of the leaf 7 is engageable within the recess 5 of the head 4.

50 In order to disengage the leaf 7 from the

head 4, it is only necessary that a screw driver or similar tool be inserted under the leaf to lift the same from engagement within the recess 5. The leaf will then pivot on the rivet 8, after which the pin 3 may be easily removed from association with the body 1.

55 It is to be understood that certain changes in the specific shape, size, or materials may be resorted to without departing from the spirit or scope of the invention or appended claim.

Having thus described the invention, what I claim as new and desire to secure by Letters Patent is:—

60 In a clevis formed with an opening in one end, an L-shaped member having one leg arranged through said opening, the other leg being formed with a recess extending inwardly from its free end, and a flat spring on said clevis snugly engageable within said recess 65 for tensionally retaining the pin.

65 In testimony whereof I affix my signature.

JOHN ACHATZ.
